REFRIGERATOR CAR CONSTRUCTION

Charles D. Bonsall, Chicago, Ill., assignor to
Standard Railway Devices Company, a corpora-
tion of Delaware

Application April 26, 1940, Serial No. 331,704

6 Claims. (Cl. 62—17)

This invention relates to refrigerator cars used to transport perishable commodities at a predetermined temperature. The essential features of a refrigerator car are an insulated body to prevent or retard ingress of heat during warm weather and egress of heat during cold weather and a cooling means and a heating means to be used during warm and cold weather respectively.

This invention applies particularly to cars in which the cooling means, preferably containers for water ice, eutectic ice, brine or dry ice, are disposed immediately below the roof of the car. The lading is supported in spaced relation to the floor by a foraminous rack. Flues, preferably associated with the side walls of the car, communicate between the cooling means and the space under the floor rack to provide a path for the circulation of air. The path is from the cooling means downwardly through the aforementioned flues, through the space under the floor rack, upwardly through the lading compartment thereby cooling the lading, and finally to the cooling means from where the cycle is repeated.

It is common in a car of this type to provide drip pans below the refrigerant containers for the dual purpose of directing the circulating air into the side wall flues and for catching the overflow and/or condensation from the containers and draining such overflow and/or condensation into the side wall flues. The drip pans are often hinged to the side walls of the car and supported by a latch or other detachable means near the center of the car. The purpose of hinging the drip pans is to facilitate the cleaning and repairing of the drip pans, refrigerant containers or other parts of the car.

An object of the invention is to provide a means to hinge the drip pan, which means does not infringe to any considerable extent upon the lading space of the car.

Another object is to prevent the dripping of condensed moisture from the hinges upon the lading. Bare metal surfaces in a refrigerator car are usually cold and condense moisture from the air if the humidity of the air is high.

Another object is to provide a hinging means which embodies a substantially water-tight although rotative connection between the drip pan and the side wall flue, thereby preventing leakage of liquid from the drip pan into the lading space.

A further object is to provide a hinging means for the drip pan which supports the drip pan rigidly when in a horizontal position and which

permits the drip pan to be easily removed when desired.

Other objects and advantages of my invention will be apparent from the following detailed description by referring to the accompanying drawings.

In the drawings:

Fig. 1 is a partial transverse section of a refrigerator car embodying my invention.

Fig. 2 is an enlarged view of the hinge means shown in Fig. 1.

Fig. 3 is a section to an enlarged scale on line 3—3 of Fig. 1.

Fig. 4 is similar to Fig. 2 and shows the drip pan in a depending position.

Fig. 5 is similar to Fig. 4 and shows the drip pan after having been raised from the position shown in Fig. 4 to disengage the hinge means.

Fig. 6 is similar to Fig. 2 but is taken through an inner post wherein said inner post is wood.

The general parts of the refrigerator car shown are insulated roof 2; side wall 3; floor 4; hatch 5; refrigerant containers 6; side wall flue 7; foraminous floor rack 8 and space 9 between the rack

25 and floor 4. A refrigerant container 6 is positioned directly below the roof 2 and adjacent a side wall 3. A drip pan 12 is provided below the container 6 and a partition 14 is disposed in an upstanding position at the edge of the drip pan

30 12. The drip pan 12 and partition 14 cooperate with the roof 2 and the upper part of the side wall 3 to form an enclosing structure 11 around the container 6, an air inlet opening 15 being provided by spacing the partition 14 from the roof

35 2. An air discharge opening 17 leads from the enclosing structure 11 to the flue 7 at a lower elevation than the air inlet opening 15. Cars of this type commonly have a row of refrigerant containers 6 near each side wall 3 and spaced apart at the center of the car. The partitions

40 14 are also spaced apart to form a duct 16 which communicates between the lading compartment 18 and openings 15.

Air circulation is as follows: Air in the lading compartment 18 is warmed by contact with the lading and rises through the duct 16 to enter the enclosing structures 11 through the air inlet openings 15. The air is cooled by contact with the refrigerant containers 6 and falls by reason of its 45 lower temperature and therefore greater density through the discharge openings 17 and flues 7 to the spaces 9 whence it rises through the rack 3 to the lading compartment 18.

The side wall 3 of the car is comprised of a series of spaced apart outer posts 25 and a series

of spaced apart inner posts 26 disposed in spaced relation to the outer posts 25. Flue sheets 28 extend between and are secured to the inner surfaces of the inner posts 26 and are provided with outwardly projecting panels 29 between the inner posts 26. A lining 31, preferably plywood or other relatively rigid insulating material, is disposed in flatwise relation with the flue sheets 28, thereby forming the side wall flues 1 between the lining 31 and the outwardly projecting panels 29 of the flue sheets 28.

Means 35 are provided to hinge the drip pan 12 adjacent (preferably above) the upper edge of the side wall lining 31, and a suitable latch 34 is preferably provided to support the opposite edge 33 of the drip pan 12. The hinge means 35 comprises a member 36 preferably extending longitudinally of the car and having the lower part 38 thereof secured, preferably by the rivets 39, to the inner side posts 26. Said lower part 38 is preferably interposed between the flue sheet 28 and the lining 31; recesses 41 may be provided in the lining 31 to receive the rivet heads 42. The upper part 44 of the member 36 is flared toward the lading compartment 18 and is provided with a recess 45 facing away from the lading compartment 18; that is, toward the side wall 3. The upper edge 47 of the member 36 is spaced a substantial distance from the flue sheet 28. The hinge means 35 also comprises a piece 48 having its upper part 50 secured to the drip pan 12 and its lower part 51 preferably depending from an edge of the drip pan. The lower part 51 of the piece 48 is directed toward the interior of the car and is formed with a part 53 substantially complementary to the recess 45. The part 53 nests within the recess 45 and the piece 48 also has an intermediate part 55 in contact with the flue sheet 28 above the lining 31. The piece 48 is thus snugly interposed between the recess 45 and the side wall 3.

It is evident from Fig. 2 that when the drip pan 12 is in the substantially horizontal position shown it is prevented from moving to the right by the contact between the recess 45 and the part 53 of the piece 48 and to the left by contact between the flue sheet 28 and the intermediate part 55 of the piece 48. Vertical movement of the hinged end 61 of the drip pan 12 is prevented by the contour of the recess 45. The recess 45 and the part 53 of the piece 48 nesting therein are preferably elements of a cylinder so that the hinge 35 permits rotation of the drip pan on a substantially horizontal axis.

When it is desirous to disengage the hinge means 35, the drip pan 12 is rotated to the depending position shown in Fig. 4 and then lifted vertically by a linear movement to the position shown in Fig. 5, where the drip pan 12 is entirely disengaged from the side wall 3 of the car. The space between the flue sheet 28 and the upper edge 47 of the member 36 is slightly greater than the width of the part 53 of the piece 48 to permit such disengagement.

Fig. 6 shows a modified construction wherein the inner side wall posts 65 are wooden members and wherein the member 36 of the hinge means 35 is secured to the inner posts 65 by lag screws 66.

The nominal size of a refrigerator car is indicated by the minimum interior width and the minimum interior height. A hinge means which projects into the lading compartment 18 has the effect of decreasing either the nominal height or the nominal width of the car, or both, for

the reason that the minimum height is the distance from the floor to the lower side of the hinge and the minimum width is the distance between the hinges on opposite sides of the car. In my invention I position the hinge means 35 substantially within the vertical confining planes of the side wall lining 31 so as not to restrict the nominal interior dimensions of the car.

The air circulating within a refrigerator car usually has a high humidity due to contact with the ice and melted ice and also possibly due to the absorption of moisture from certain types of lading. When this humid air comes in contact with bare metal parts, a considerable part of the moisture is condensed therefrom onto the metal parts. There is a tendency for such condensation to drip from the metal parts and, in many cases, ruin or damage the lading. In my construction the exposed metal parts of the hinge means 35 are arranged to overlie the lining 31 so that moisture dripping therefrom does not drip upon the lading.

The accompanying drawings illustrate the preferred form of the invention, though it is to be understood that the invention is not limited to the exact details of construction shown and described, as it is obvious that various modifications thereof within the scope of the claims, will occur to persons skilled in the art.

I claim:

1. In a refrigerator car having a lading compartment, a wall, means including a lining associated with said wall for forming a flue, a drip pan and means to hinge said drip pan to said wall adjacent the upper edge of said lining, said hinge means comprising a member secured to said wall and formed with a recess facing said wall, and a piece secured to said drip pan with a part thereof nesting in said recess, the engaging parts of said member and said piece being confined substantially within the vertical planes of said lining so as not to encroach upon said flue or said lading compartment.

2. In a refrigerator car having a wall, a refrigerant container adjacent said wall, a lining forming a part of said wall and having a flue on one side and a lading compartment on the other side thereof, a drip pan below said container, and means to hinge said drip pan to said wall adjacent the upper edge of said lining, said means comprising a continuously extending member carried by said wall and formed with a recess facing the wall and a continuously extending piece secured to said drip pan and having a part nesting in said recess and snugly confined therein by a part of said wall, whereby liquid from said container is directed into said flue.

3. In a refrigerator car having a wall, a refrigerant container adjacent said wall, a lining forming a part of said wall and having a flue on one side and a lading compartment on the other side thereof, a drip pan below said container, and means to hinge said drip pan to said wall adjacent the upper edge of said lining, said means comprising a member carried by said wall and a continuously extending piece secured to said drip pan and operatively engaged with said member, said member and piece being substantially coextensive with said drip pan whereby liquid from said container is directed into said flue, said member and said piece being rotatively engaged to permit swinging said drip pan about the hinge means.

4. In a refrigerator car having a wall, a refrigerant container adjacent said wall, a lining

forming a part of said wall and having a flue on one side and a lading compartment on the other side thereof, a drip pan below said container, and means to hinge said drip pan to said wall adjacent the upper edge of said lining, said means comprising a member carried by said wall and a continuously extending piece secured to said drip pan and operatively engaged with said member, said member and piece being substantially coextensive with said drip pan whereby liquid from said container is directed into said flue, said member and said piece being rotatively engaged to permit swinging said drip pan about the hinge means and proportioned to be disengaged only when said drip pan is depending in a substantially vertical plane from the hinge means.

5. In a refrigerator car having a wall including lining means, a refrigerant container adjacent said wall, said car including a lading compartment and a flue disposed on opposite sides of said lining means, drip pan means below said container and structure for pivotally securing said pan means to said wall adjacent the upper

edge of said lining means, said structure comprising an element carried by one of said means coextensive with said drip pan means, and means carried by the other of said means cooperative with said element to form a hinge, said element being constructed and arranged to direct liquid from the container into said flue.

6. In a refrigerator car having a wall including lining means, a refrigerant container adjacent said wall, said car including a lading compartment and a flue disposed on opposite sides of said lining means, drip pan means below said container and structure for pivotally securing said pan means to said wall adjacent the upper

10
